CLAIM

The ornamental design for a low profile cell phone car
charger, as shown and described.

DESCRIPTION

A portion of the disclosure of this design patent document
contains material to which a claim of copyright protection is
made. The copyright owner has no objection to the facsimile
reproduction of the patent document or the patent disclosure
as it appears in the U.S. Patent and Trademark office file or
records, but reserves all other copyright rights.

FIG. 1 is a perspective view of a low profile cell phone car
charger, in accordance with the present invention.

FIG. 2 is a top plan view thereof.

FIG. 3 is a front elevation view thereof.

FIG. 4 is a right elevation view thereof.

FIG. 5 is a left elevation view thereof.

FIG. 6 is a back elevation view thereof; and,

FIG. 7 is a bottom plan view thereof.
